UNITED STATES PATENT OFFICE

2,009,468

POST-POCKET

Harry T. Anderson, Butler, Pa.

Application January 26, 1933, Serial No. 653,658

8 Claims. (Cl. 105—391)

This invention relates to post or stake pockets, such as are used on gondola freight cars into which stakes may be put for the purpose of increasing the effective height of the car side walls, and thereby adapt the cars for the hauling of certain freight, such as lumber and other articles that require a considerable amount of space in proportion to their weight.

The stake pocket embodying this invention is 10 in some respects similar to the stake pocket disclosed in my United States Letters Patent 1,363,-364 granted June 14, 1932. This patent discloses a collapsible pocket, which when a post or stake is removed therefrom, automatically falls 15 against the side sheet of the car, which position it occupies until manually reset to post receiving or operative position. When hanging along the side sheet of the car, the pocket is out of the way and not likely, if ever, to be injured or broken 20 when the car is being loaded with freight of a character or quantity not requiring the use of posts or stakes.

An object of this invention is the provision of a collapsible post pocket adapted to fall automatically against the side sheet of the car when the stake is removed, in the same manner as the pocket disclosed in the above mentioned patent, but which in some respects, shall be simpler in construction and more easily manufactured than 30 the pockets of said patent.

In the patent above mentioned, the post or stake receiving member is hinged on the side sheet of the car and the strut which holds the same in operative position is hinged to said member. Thus when the stake or post is removed, the post receiving member and strut fall against 35 the side of the car as an articulated unit.

An object of this invention is to make the strut and post receiving member as separate units 40 or parts, mount each part in a bearing on the side sheet of the car, and provide for such coaction between them that the strut will hold the post receiving member in operative relation to receive and hold a stake, and that both parts will automatically disengage and fall or swing against the 45 side sheet upon removal of the post or stake.

The stake pocket of the patent is open on the side adjacent the side sheet of the car, so that when a stake or post is driven into the pocket, 50 the stake bears directly against the side sheet and renders the same liable to damage.

An object of this invention is the provision of a stake or post pocket that shall maintain the stake in spaced relation to the side sheet of the 55 car.

A further object of the invention is the provision of means for maintaining a stake or post in spaced relation to the side sheet of a car as the same is driven home in stake pockets mounted on the side sheet.

Other objects of the invention will, in part, be apparent, and will, in part, be obvious from the following description taken in conjunction with the accompanying drawings in which:—

Figure 1 is a view in vertical section through one side of a gondola car showing two stake pockets embodying one form of the invention, mounted in vertical alignment on the car side sheet with a post or stake extending therethrough;

Fig. 1a is an enlarged top plan view of the stake or post pockets illustrated in Fig. 1 as seen looking in the direction of the arrows on line Ia—Ia of Fig. 1, one of the bearings for the post receiving member being shown in section;

Fig. 2 is a view in section of the post pocket taken on line II—II of Fig. 1a.

Fig. 3 is a view in side elevation of the post or stake receiving member of the pocket shown in Figs. 1 and 2;

Fig. 4 is a view showing the shape of the side bars of the post receiving member taken on line IV—IV of Figs. 1a, 2 and 3;

Fig. 5 is a rear elevational view of the post receiving member as seen looking in the direction of the arrows on line V—V of Fig. 3;

Fig. 6 is a top plan view of a strut embodied in the post pocket assembly illustrated in Figs. 1, 1a, and 2;

Fig. 7 is a view similar to Fig. 1 showing stake pockets embodying a modified form of the invention, and adapted for use on cars having side plates that project inwardly from the car side sheet;

Fig. 7a is an enlarged top plan view of the post pockets of Fig. 7 as seen looking in the direction of the arrows on line VIIA—VIIA of Fig. 7;

Fig. 8 is a fragmentary view in vertical section of the side sheet of a gondola car showing a side elevational view of a post or stake pocket, embodying another form of the invention, the pocket being in operative position to receive a post or stake.

Fig. 9 is a view in section of the post receiving member taken on line IX—IX of Fig. 7a; and

Fig. 10 is a view in section of the side bars of the post receiving member taken on lines X—X of Figs. 7a and 9.

Throughout the drawings and the specification, like reference characters indicate like parts.

In Fig. 1 of the drawings, one side of a gondola type freight car is illustrated on which stake pockets 1 embodying one form of the invention are mounted in vertical alinement to receive a post 5 or stake P. In regard to the portion of the car illustrated, 2 designates the car side sheet, 3 the floor, 4 the bottom side sill or plate and 5 the top side plate. The top side plate extends outwardly from the car side sheet so that the stake or post P 10 may be positioned relatively close thereto. The pockets are designed to be manually placed in operative position and to automatically fall against the side sheet upon removal of the post or stake. Also, as will be apparent later herein, 15 the post pockets are so constructed that the posts or stakes will not touch the side sheet even during the time that the stakes are being driven into the same.

In Figs. 1a and 2, enlarged views of the post 20 pocket 1 are illustrated. Pockets 1 may be mounted either on the inside or the outside of the car side sheet 2. For convenience, it may be assumed that pockets 1 are located on the inside of the car.

Each pocket 1 comprises a post or stake receiving member 6 and a strut 7, each independently journaled in bearings A and B, respectively, formed in supporting straps 8 secured to the side sheet 2, two straps 8 being provided for each 30 pocket as shown in Fig. 1.

Post receiving member 6 may be made of steel or alloy steel either cast or forged and comprises front and rear bars 9 and 10 connected by side bars 11, and trunnions 12 formed as extensions at 35 the ends of the rear bar 10. Thus the side and cross bars form an opening O to accommodate a post or stake P.

The rear bar 10 of each pocket being adjacent the side sheet, it will be apparent that the post 40 or stake will be spaced from the side sheet. Since two pockets are used with each stake, and since these pockets are placed in vertical alinement, the stakes will not be driven against the side sheet while being driven into place. The rear bar 10 45 of these pockets therefore acts as a spacer and a bearing for the posts or stakes thereby relieving the side sheets of stresses and strains for which they are neither designed nor intended to endure.

In order that the post receiving member may be of relatively light weight and possess great strength and rigidity, it is preferred that the side bars be given the shape in transverse section indicated by Fig. 4, the front and rear bars the 55 shape shown in Fig. 2, and the trunnions the shape illustrated in Figs. 1a, 3 and 5.

The side bars are shaped with inner and outer vertical flanges 13 and 14 connected by a horizontal web 15. The inner flanges 13 of the side 60 bars may be made to extend higher above the webs 15 than the outer flanges 14, (see Fig. 4). The front bar may be formed with an upwardly extending rib or flange 16 the ends of which merge with the outer ends of flanges 13.

The inner and outer portions 17 and 18 of the trunnions 12 may be given a somewhat H-shape in section and these portions may be separated by a circular flange 19. The trunnion flanges 70 19 contact with bearings A of straps 8.

The rear bar 10 is substantially oval in transverse section, the lower rear surface 21 of which is substantially concentric with the circular flanges 19. This surface is tangent, or substantially so, to the side sheet and bears against the 75

same for substantially the entire distance between the bearing straps 8.

The upper portion 22 of the rear surface of the rear bar is spaced from the side sheet when the post receiving member 6 is in post receiving position (see Figs. 1a and 2), but acts as a stop to limit the amount by which the same may turn in the direction of arrow 23 when a stake is being removed as will be made apparent later herein.

The under side of the front cross bar may be formed with a groove 24 of somewhat U-shape to receive the forward end of strut 7 and hold member 6 in operative position, that is, in position to receive and hold a stake or post.

Strut 7 may be formed from round rod of steel or iron bent to the shape illustrated in Fig. 6, or it may be made of cast steel or iron. The strut includes trunnions 25, and a front cross bar 26 connected by diverging portions 27.

The trunnions of strut 7 are journaled in bearings B of straps 8 so that the strut is free to turn therein, and when swung to the position shown in Fig. 2, the front cross bar 26 thereof will register with groove 24 of post receiving member 6.

In operation, the post receiving member is swung upwardly to a position such that, when the strut is also swung upwardly, the cross bar 26 of the strut clears the underside of the front cross bar 9 of post receiving member 6. Member 6 is then lowered so that the strut cross bar will nest in groove 24. When two vertically alined pockets have been placed in operative position as described, post or stake P may be driven through openings O thereof as indicated in full lines in Fig. 1 or in broken lines in Fig. 1a.

As the stake is being driven home, the rear cross bars 10 of the post receiving members serve to space the stake from the side sheet, to hold 40 the stake in alinement vertically, and to relieve the side sheet of load strains imposed on the stakes.

When a post is removed, by pulling the same upwardly, the post receiving members turn in 45 the direction of arrow 23 until the upper portions 22 of the rear cross bars strike the side sheet preventing further turning thereof. The post receiving members are substantially horizontal when this occurs, but when in such position, the struts are disengaged automatically from grooves 24 and swing down against the side sheet of the car to the position indicated by broken lines in Fig. 2. The moment the post or stake is removed from members 6, these members swing 55 down against the side sheet as indicated in broken lines in Fig. 2.

Thus it is apparent that post or stake pockets may be placed manually in operative or stake-receiving position and that the pockets will automatically collapse and the component parts thereof swing down against the side sheet of the car to inoperative position by the act of removing the stake or post therefrom.

The post pocket described in connection with Figs. 1 and 2 is applicable to cars on which the side plates, at the top of the side sheet extend outwardly from the sides of the car. The post pocket shown in Figs. 7, 7a and 8 is designed for use on cars provided with side plates that extend inwardly from the sides of the car and would interfere with the proper functioning of the pockets illustrated in Figs. 1 and 2.

In Figs. 7, 7a and 8, 2 designates the side sheet

of a gondola car having a side plate 29 secured to the top thereof and extending laterally inward a substantial distance from the side on which the post pockets 30 are mounted. For this reason, the post receiving member is made longer than the post receiving member 6 of the pocket 1 so that the stakes will clear the side plate when placed in the pocket. Pockets 30 each comprises a post receiving member 31 and a strut 7 both of which are hinged or journaled independently of each other in bearings A and B of straps 8 secured to the side sheet.

Member 31 may be made either as a forging or a casting, and includes front and rear cross bars 32 and 33, side bars 34 and trunnions 35 formed, in effect, as extensions of the rear bar 33. The front and side bars may be made somewhat H-shape in section so as to give strength and rigidity to the post receiving member and still maintain the weight thereof relatively low. The rear cross member may be of somewhat T-shape with the lower rear side thereof formed as an arc of a circle so that such portion will lie tangent to the side sheet as the post receiving member is swung to post receiving position or to inoperative position. The trunnions are also made somewhat H-shape in section as may be apparent by inspection of Fig. 8, with the inner and outer portions thereof separated by a circular rib or flange 35' which at all times has full contact with the bearings A of straps 8. The portions of the trunnions on either side of these flanges which are circular and of the same curvature as the ribs also provide a bearing surface for the trunnions in the bearings A.

In order that struts 7 may have operative engagement with post receiving members 31, an intermediate cross bar 36 is formed at about the middle of the post receiving member and directly below the innermost edge of the side plate 29. This cross bar is provided with an abutment or recess 37 into which cross bar 26 of the strut may be placed when the post receiving member is to be held in post receiving position as indicated in Figs. 7 and 8.

The cross bar 36 forms also the rear side of the post receiving opening O' through which the post extends, the post being indicated by dot and dash lines in Fig. 8 and in full lines in Fig. 7.

The rear portion of the post receiving member may be formed with a web 39 having an aperture 40 to reduce the weight of the post receiving member and to strengthen and rigidify the rear portion of the post receiving member. Also, the rear bar 33 and the trunnions 35 of post receiving member 31 provide a continuous bearing across the side sheet from one bearing strap 8 to the other thereby minimizing the stress of the pocket on the side sheet.

In operation, assuming that the post pockets are in the inoperative position indicated by the broken lines in Fig. 8, post receiving members 31 are swung upwardly until approximately in horizontal position, the limiting position as fixed by portions 41 of the rear cross bar. Portions 41 of the rear cross bars strike against or abut the side sheet 2 when the post receiving members are in horizontal position. When in such position, the struts may be swung up to that position in which the cross bars 26 thereof may register in the grooves 31 of the post receiving members when the same are lowered to the full line position indicated in Fig. 8. The post or stake may now be inserted through the post receiving openings O' and driven to the position indicated in Fig. 7.

While the stakes are being driven into place, the rear cross bars 36 of the pockets keep them in upright position and in spaced relation to the side sheet thereby protecting the same against injury. Also after the stakes have been driven home, the rear cross bars hold the stakes securely within the apertures O' of the pockets so that any bending strains imposed on the stakes will not be directly transmitted from the stakes to the side sheet.

Thus in both forms of pockets the rear cross bars act as spacers to separate the stakes or posts from the side sheets and as retainers for holding the stakes securely and positively within the pockets.

When a car has been unloaded and it is desired to remove the stakes or posts, the posts are merely driven upwardly. By driving the posts upwardly, the post receiving members swing upwardly to their limiting positions as fixed by portions 41 of the rear cross bars, in which position the struts become disengaged from the grooves 37 and swing downwardly against the side sheet of the car as indicated by the broken line position in Fig. 8.

The moment the post is removed from the post receiving members 31 these members also swing downwardly to the broken line position indicated in this figure.

Thus, it will be apparent that the post receiving members indicated in Figs. 7, 7a and 8 function in identically the same manner as the post receiving members illustrated in Figs. 1, 1a and 2 and differ therefrom only in that the post receiving aperture O' or opening in member 31 extends far enough away from the side sheet of the car to clear any obstruction, such as side plates 29, which would otherwise interfere with the insertion of the post or stakes into the post receiving members.

While various modifications and changes may be made in the post receiving pockets herein disclosed, it will be apparent and it is to be understood by those skilled in this art that such changes may be made without departing either from the spirit or the scope of the invention. It is desired, therefore, that only such limitations shall be placed on the invention as are imposed by the prior art and the appended claims.

What I claim as new and desire to secure by Letters Patent is:

1. A post pocket for gondola freight cars comprising a post-receiving member pivotally mounted on the side of the car and adapted to frictionally grip the post, said receiving member being normally free to swing downwardly against the car side, and a supporting member disposed below the post-receiving member and pivotally mounted on the side of the car adapted when swung to operative position to releasably engage the post receiving member and hold it in operative position to receive a post, said post receiving member being adapted to automatically release the supporting member to inoperative position by the act of removing a post therefrom, the post receiving member falling to inoperative position automatically upon removal of said post.

2. A post pocket for gondola freight cars comprising a post receiving member adapted to frictionally grip a post and a supporting member therefor, both adapted to be pivotally mounted on the side of a car and being normally free to swing downwardly towards the same to inoperative position, there being an abutment on the post receiving member adapted to be releasably

engaged by the supporting member when both members are swung upwardly to operative position, the post receiving member being disposed to automatically release the supporting member, by the act of removing a post therefrom, to inoperative position, and upon removing the post, the receiving member also returning automatically to its normal or inoperative position.

10 3. A post pocket for freight cars comprising a post receiving member adapted to be pivotally mounted on the side of a car, and to frictionally grip the sides of the post, and a supporting member adapted to be pivotally mounted on the side 15 of the car and arranged to releasably engage the post receiving member at a point remote from its mounting and hold the same in operative position to receive a post, said members being arranged to be automatically disengaged upon the removal of the post and to fall downwardly towards the side of the car to inoperative position.

20 4. A post pocket for freight cars comprising a post receiving member adapted to frictionally grip the post and a supporting member therefor 25 both provided with trunnions whereby each may be pivotally supported in mountings on the side of the car, the post receiving member having an abutment on the under side thereof at a point remote from its mountings adapted to be engaged 30 by the supporting member when both members are swung to operative or post receiving position, said members being automatically disengaged from each other upon the removal of a post and adapted to swing by gravity towards the 35 side of the car to inoperative position.

40 5. A collapsible post pocket comprising a post receiving member having integrally formed front and rear cross bars, side bars and trunnions formed as extensions of the rear bar, said bars forming an opening through which a post or 45 stake may be passed and the trunnions being adapted to pivotally support said member in bearings on the side of the car, and the rear bar being adapted to space the post from the car side and to form a bearing for the side of the post adjacent the car side, and a strut pivotally mounted on the side of the car for releasably engaging and supporting the post receiving member in post receiving position, the post receiving member and strut when disengaged from each other swinging downwardly by gravity to inoperative position.

50 6. A post pocket for freight cars comprising

a post receiving member pivotally mounted on the side of the car and being normally free to swing towards the side of the car to inoperative position, a cross member adjacent the side of the car and extending across one side of the post receiving space of said post receiving member adapted to maintain the post in spaced relation to the side of the car, and means for holding said post receiving member in post receiving position, the post receiving member frictionally gripping the post so that when the post is pulled upwardly and out of the same said holding means is automatically disengaged from the post receiving member thereby allowing it to swing to inoperative position upon removal of the post therefrom.

7. A post pocket for gondola freight cars comprising a post-receiving member pivotally mounted on the side of the car and being normally free to swing downwardly against the same, there being a rigid member adjacent the side of the car and extending across the rear side of the post receiving member adapted to space the post from the side of the car and form a bearing for one side of the post, and a supporting member disposed below the post-receiving member and pivotally mounted on the side of the car adapted when swung to operative position to engage the post receiving member and hold it in operative position to receive a post, said post receiving member when moved upwardly a predetermined distance releasing the supporting member so that it may swing to inoperative position.

8. A collapsible post pocket comprising a post receiving member having integrally formed front and rear cross bars, side bars and trunnions formed as extensions of the rear bar, said bars forming an opening through which a post or stake may be passed and the trunnions being adapted to pivotally support said member in bearings on the side of the car, and the rear bar being adapted to space the post from the car side and to form a bearing for the side of the post adjacent the car side, the trunnions and rear bar providing a continuous bearing against the car side, and a strut adapted to be pivotally mounted on the side of the car for releasably engaging and supporting the post receiving member in operative position, the post receiving member and strut when released from each other both 40 swinging downwardly by gravity to inoperative position.

HARRY T. ANDERSON.
